US0D1042708S

(12) United States Design Patent (10) Patent No.: US D1,042,708 S
(45) Date of Patent: * Sep. 17, 2024

(54) FIREARM SLIDE

(71) Applicant: HS Produkt D. O. O., Karlovac (HR)

(72) Inventors: Mariojo Špine, Karlovac (HR); Dennis J. Reese, Geneseo, IL (US); Stephen H. McKelvain, Geneseo, IL (US)

(73) Assignee: HS Produkt D.O.O., Karlovac (HR)

() Term: 15 Years

(21) Appl. No.: 29/735,728

(22) Filed: May 22, 2020

Related U.S. Application Data

(63) Continuation-in-part of application No. 35/506,775, filed on Feb. 13, 2019 (U.S. filing date under 35 U.S.C. 384), and having an international filing date of Feb. 13, 2019, now Pat. No. Des. 894,310.

(57) CLAIM

The ornamental design for a firearm slide, as shown and described.

DESCRIPTION

FIG. 1 is a front perspective view of the firearm slide showing our new design;

FIG. 2 is a back perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a back view thereof.

The broken lines illustrate portions of the firearm slide or environmental structure that form no part of the claimed design.

1 Claim, 6 Drawing Sheets
